UNITED STATES PATENT OFFICE

EDWIN FITCH NORTHRUP, OF PRINCETON, NEW JERSEY, ASSIGNOR TO AJAX ELECTRO-THERMIC CORPORATION, OF AJAX PARK, EWING TOWNSHIP, NEW JERSEY, A CORPORATION OF NEW JERSEY

INDUCTION ELECTRIC FURNACE

Application filed July 17, 1929. Serial No. 378,834.

My invention relates to electric furnaces intended to melt finely divided turnings or other scrap.

One purpose of my invention is to so charge the turnings as to cause the pressure of the weight of the turnings to compress the turnings in the crucible.

A further purpose of my invention is to charge the turnings through a stack, thus artificially increasing the height of the column of turnings whose weight normally tends to feed the turnings into the furnace crucible.

A further purpose is to use a stack for charging a furnace and to remove the stack for completion of the operation of melting and pouring, permissibly using the stack during this time for the filling of another furnace crucible.

A further purpose is to preheat the turnings by an inductor coil located at an intermediate point in their passage to the crucible, reducing the percentage of turnings which still are magnetic after they reach the crucible so as to improve the power factor of crucible inductor coils and to secure nearly uniform magnetic conditions within both the coils.

A further purpose is to inductively heat scrap magnetic material at two different points, one on its way to the crucible and the other within the crucible, both while the scrap is under compression by a head of scrap above it, permitting substantial uniformity of power factor correction within the preliminary heating inductor and greater uniformity of power factor correction for the coils about the melting crucible.

A further purpose is to use the turnings or other scrap to be melted as a weight to make the pile more compact at the lower end and to melt inductively where the scrap is relatively compacted.

A further purpose is to melt finely divided and little compacted machine turnings without preliminary cabbaging and by direct induction of high frequency current within the turnings.

A further purpose is to apply multiphase current to separate inductors acting upon scrap having different magnetic conditions but part of the same charge, one inductor for

each phase, thus reducing the cost of the machine per unit of power furnished.

Further purposes will appear in the specification and in the claims.

My invention relates both to the methods or processes involved and to apparatus by which they may be carried out.

Figure 1 is a top plan view of one embodiment of my invention.

Figure 2 is a side elevation of the structure seen in Figure 1.

Figure 3 is a section of Figure 2 taken upon line 3—3.

Figure 4 is a diagrammatic side elevation of a furnace of the general type included in Figure 1 but differing in detail.

Figure 5 is a central vertical section of structure shown in Figure 4 taken parallel to the plane of the paper.

Figure 6 is a diagrammatic view showing the swinging of the stack.

In the drawings similar numerals indicate like parts.

Where large quantities of scrap metal are handled the remelting of the scrap to recover it presents quite a problem. Melting by external applied fuels has been quite unsatisfactory and melting by arc furnaces has greatly altered the composition of the metal.

In addition to the variation in the chemical composition of the metals or alloys, it has been necessary for arc melting that the materials be cabbaged preliminarily. The concentration of metal in the loose scrap is very low, reaching a percentage for fine steel turnings less than 5% of the total bulk, and plants for cabbaging such material are quite expensive. The additional cost of handling to transport the cabbaged scrap greatly increases the expense.

My invention makes possible very satisfactory handling and melting of the scrap at the plant at which it was cut without necessity for cabbaging, transferring the scrap conveniently by electro-magnetic "grabs" and utilizing a high column of scrap to insure a continuous feeding to the furnace crucible and to utilize the pressure due to the weight of the scrap to condense the scrap in the

crucible. The "grab" transfer of course applies to magnetizable scrap only.

The structure shown is described in illustration and not in limitation and for the purpose only of complying with the statute 5 by explaining the best form of my invention known to me.

For convenience of operation I raise my furnaces above the normal floor level 10 so 10 that the furnaces may be accessible from a platform 11 which is approached suitably at 12. The equipment shown comprises a supporting frame 13 carrying funnel tops 14 or 14' above the several furnace crucibles 15 and 15 16 and supporting a crane mast 17. Bracket 18 carries a furnace shaft 19 which may be swung into position beneath either of the funnel charging inlets 14 or 14'. In either 20 position it spans the space between the funnel inlet and the top of the corresponding crucible 15 or 16. Independently mounted upon the crane mast is shown a bracket 20 adapted to carry a cover 21 or 21' which may be placed over either crucible when the stack or 25 shaft 19 has been moved away.

The material to be charged is lifted through any suitable crane, of which the magnet terminal 22 only is shown, and may be dropped into the funnel inlet by release of current in 30 the magnetic clutch, grip or "grab" of the crane.

The crucible is shown as capable of being tapped through any suitable outlet 23, plugged at 24 so as to permit discharge of the 35 molten content through a gutter 25.

The space 26 surrounding the furnace coil or coils 27 is circumferentially closed at its lower part so as to provide a passage to receive molten metal in case of accidental 40 breakage of or leakage through the crucible. At the bottom of this space discharge outlets 28 are closed at the top by fusible plates 29 which will stop a slight flow but which will give way to any considerable flow of molten 45 metal.

As thus far described, the construction of the platform, framework and taps may be regarded as conventional, but the use of the stack, the moving of the stack into and out of 50 position above the crucible or the crucible from beneath the stack, the capability of using the stack and cover for any of different furnaces, and the use of a safety plate to safeguard the furnace and allow flow of leakage 55 metal away from it are believed by me to be novel and to be of broad application in many other settings than the setting shown.

In Figures 4 and 5 slightly different detail is shown of the crucible and stack, and conventionally shown furnace windings in novel 60 location and relation are illustrated capable of use with the stack of Figures 1-3, or with any other form of stack and its furnace.

In Figure 4 inductor coils 27 and 30 are 65 shown conventionally, one surrounding the

crucible and the other surrounding the stack and fed from the supply lines 31, 32 and 33 of a two-phase system.

In Figure 5 coils 27', 27² and 30' are shown conventionally, the coil 30 surrounding the 70 lower part of the stack and the coils 27' and 27² surrounding the crucible. The coil 30' is shown as fed by a supply of current from lines 31', 32' whereas the coils 27', 27² are fed from a two-phase circuit through lines 31, 32 75 and 33.

Obviously single phase or a different number of phases than two-phase could be used to supply the coils surrounding the crucible with or without supply to the coils surrounding the stack and the same sources of current 80 can be used for supplying the stack and crucible coils if desired.

Where the stack is made of electrically conducting material it is desirable to break its circumferential continuity at one or more places to prevent dissipation of energy within the stack and such an interruption is shown conventionally by a vertical slit 34 in the 85 lower part of the wall of the stack.

Obviously there are many ways by which induced current flow within the stack may be sufficiently prevented so that the current will be confined within the content rather than within the casing or shell. This is of 90 importance because heating of the finely divided product by heat conductivity from the shell would be very slow and inefficient, whereas heating by current induced within the content is rapid and highly effective with 95 high frequency current.

The character of attachment of the funnel inlet in Figures 4 and 5 as compared with the earlier figures is not regarded by me as of much importance as the figures are largely 100 diagrammatic and are intended to show suggested forms rather than necessary constructions.

In operation there is no necessity for having an initial pool into which the turnings 110 are forced though such a pool initially or as formed assists in the melting. If the metal were solid the extent of penetration of the induced current within the charge would be very small, but because of the small total volume of metal, a considerable depth of penetration within the metal will occur, heating to 115 great advantage.

The weight of the column of scrap not only increases the density of the scrap at the lower part of the column so that the current will not be induced in the scrap to as great a depth as would otherwise be the case but greatly improves the contacts of individual 120 parts of scrap with each other to facilitate 125 passage of the current.

Because of the small volume of scrap as compared with the volume of this same scrap when melted, a supply of scrap in the stack 130 high enough to fill the crucible with molten

metal would involve an excessive height of stack. This is taken care of by progressively feeding quantities of scrap through the same stack length until the required quantity has been supplied.

As the furnace crucible can be handled and emptied in any way desired after removal of the stack from a position over it, I wish to point out that provision for tapping a stationary crucible is not intended by me to indicate that the crucible need be of stationary type.

Because of the very low concentration of metal in uncabbaged scrap such as turnings the depth of penetration of the induced current within the scrap is relatively very high, too high for good power factor conditions if the frequency were not high. The high frequency is further very beneficial in the very rapid rate of change secured by this frequency, the consequent high rate of power input throughout the content and the improved flow of current across the poor contacts between adjoining fragments of the charge.

Whereas in previous operations upon scrap, including turnings it has been assumed that it was necessary to have an initial pool of molten metal into which the scrap can be submerged I find that this is not necessary with my invention. Though I could feed my scrap into an initial pool, my invention is entirely practical starting with a furnace substantially free from molten metal content and continuing operation until the molten content reaches any desired approach to the full permissible content of the furnace.

In operation, feeding of the turnings or other scrap to the shaft will be stopped when the molten content of the furnace and the anticipated molten metal from the content of the shaft will fill the furnace with molten metal to the desired depth. All of the content is then melted down into the furnace after which the shaft will be moved away from the top of the furnace while the furnace is tapped of its molten content. This can be done whether it be the intention to use the shaft or stack in the filling of an additional furnace in the meantime or not.

The placing of a coil about the lower part of the stack heats the content within the stack to a high degree before it enters the furnace, avoiding the relative chilling of the furnace which would otherwise take place and reducing the time taken for the melt. Since this coil about the stack may be controlled to operate upon magnetic metal only, by controlling the power input and through it the temperature at which the metal leaves this part of the stack, the inductance of this coil will be substantially constant and the power factor of the circuit feeding this coil may be maintained quite high and nearly free from fluctuation.

For the same reason that there will be a

smaller amount of magnetizable metal within the furnace pool than would otherwise be the case the power factor of the circuit or circuits feeding the coils about the furnace crucible may be kept high and substantially constant. 70

Before magnetizable scrap loses its magnetism the frequency used can advantageously be lower than that desirable after it has lost its magnetism.

It will be obvious that the diameter of the crucible and hence the diameter of the stack can be made large enough to avoid induction of current beyond the center of the charge. Except for this desideratum the size of the crucible will be determined largely upon the 80 basis of the desirable size for handling the type of charge.

In the discussion steel or iron turnings have been contemplated, as the utility of the furnace will probably be greater for handling 85 a magnetic than for non-magnetic scrap, but it is evident that the invention is applicable also to scrap of non-magnetic metals with considerable benefit though not with all nor the same benefit as in the case of magnetizable charges.

While I have preferred to illustrate my invention by but two slight variations of the same general form, I recognize that my invention can be applied to many different forms 95 and variations and have selected those shown because they are practical, reliable and effective and at the same time well illustrate the principles of my invention.

Having thus described my invention, what 100 I claim as new and desire to secure by Letters Patent is:—

1. The method of heating and melting uncabbaged magnetizable scrap, which consists in progressively feeding the scrap in a downward direction under a pressure equivalent to a head in excess of the head obtainable from the furnace and in passing high frequency current about the scrap through separate paths comprising belts spaced along the 105 path of travel of the scrap to induce current in it to preheat it and to melt it, respectively.

2. The method of preheating and melting uncabbaged magnetizable scrap, which consists in advancing the scrap and in separately 115 inducing high frequency current within the scrap through belts of the scrap along its path of travel, the belts being spaced one from the other and located to affect the scrap respectively before and after the scrap loses its 120 magnetism.

3. The method of preheating and melting uncabbaged magnetizable scrap, which consists in artificially extending the head of scrap above that of which the furnace is located, in utilizing the additional head secured to compress the scrap and to increase the current-carrying contact and in inductively causing current to pass through the scrap so compressed. 125

4. The method of preheating and melting uncabbaged magnetizable scrap, which consists in advancing the scrap, in separately inducing high frequency current within the scrap along its path of travel before and after the scrap loses its magnetism and in correcting the power factor of the supplies for the two induced high frequency currents separately to secure advantage from substantial maintenance of the inductance of the charge at each of the points of induction.

5. The method of heating and melting uncabbaged scrap in a furnace, which consists in utilizing the weight of a mass of scrap above the furnace to feed and relatively compress the scrap and at the same time passing a high frequency electric current about the scrap at a point of relative compression by the mass to take advantage of the increased density and improved contact thus obtained.

6. The method of heating and melting uncabbaged scrap within a coreless furnace, which consists in providing a column of scrap within and above the furnace so that the scrap above the furnace by its own weight progressively increases the density and improves the contact of the individual pieces of scrap within the column and in passing high frequency current about the lower part of the column of scrap above the furnace.

7. The method of heating and melting uncabbaged scrap within a coreless furnace, which consists in providing a column of scrap within and above the furnace so that the scrap above the furnace by its own weight increases the density and improves the contact of the individual pieces of scrap within the furnace and in passing high frequency current about the scrap within the furnace to inductively heat the scrap.

8. The method of heating and melting uncabbaged scrap within a coreless furnace, which consists in providing a column of scrap within and above the furnace so that the scrap above the furnace by its own weight increases the density and improves the contact of the individual pieces of scrap within the furnace, in passing high frequency electric current about the body of scrap above the furnace and in passing high frequency electric current also about the scrap within the furnace, to separately induce current in the scrap to preheat and melt the scrap.

9. The method of melting uncabbaged scrap in a furnace, which consists in passing high frequency current about the scrap while maintaining a pressure upon the scrap in the furnace considerably in excess of that of a column of scrap having a height correspondingly to the depth of the furnace.

10. In mechanism for melting uncabbaged scrap, a high frequency coreless induction furnace adapted to induce current in the scrap and a stack above the furnace adapted to

maintain a head of scrap upon the scrap in the furnace.

11. In mechanism for melting uncabbaged scrap, a high frequency coreless induction furnace and a stack above the furnace adapted to maintain a head of scrap upon that in the furnace and a high frequency coreless furnace inductor for heating the scrap in the stack below a substantial head of scrap.

12. In an induction electric furnace, a furnace stack adapted to contain a charge, a furnace below the stack and into which charge is fed from the stack, separate inductor furnace coils surrounding the lower part alone of the stack and furnace, respectively, and high frequency electric current supply for the coils.

13. In an induction electric furnace, a furnace stack adapted to contain a charge, a furnace below the stack and into which charge is fed from the stack, separate inductor furnace coils surrounding the lower part of the stack and furnace, respectively, and adapted to induce current in the scrap and high frequency electric current supply for the coils fed from different phases of the same high frequency supply.

14. In an induction electric furnace, a furnace stack adapted to contain a charge, a furnace below the stack and into which charge is fed from the stack, separate inductor furnace coils surrounding the lower part of the stack and furnace, respectively, and high frequency electric current supply for the furnace inductor and electric current supply for the stack inductor lower in frequency than that for the furnace inductor.

15. In a mechanism for melting uncabbaged scrap, a funnel top, a removable furnace stack beneath the top, a coreless induction furnace with which the stack is adapted to cooperate and into which it is adapted to feed and high frequency coreless inductor means about the furnace for melting the scrap while it is subjected to the head of scrap within the stack.

16. In mechanism for melting uncabbaged scrap, a funnel top, a removable furnace stack beneath the top, a coreless induction furnace with which the stack is adapted to cooperate and into which it is adapted to feed, high frequency coreless inductor means about the furnace for melting the scrap while it is subjected to the head of scrap within the stack and separate high frequency coreless inductor means for heating the scrap within the stack on its way to the furnace.

17. In mechanism for melting uncabbaged scrap, a removable furnace stack adapted to hold a feeding charge, a coreless induction furnace with which the stack is adapted to cooperate and into which it is adapted to feed, and separate high frequency charge surrounding means for inducing current

within the content of the stack and within the content of the furnace.

18. In mechanism for melting uncabbaged scrap, a furnace stack capable of removal from the furnace and adapted to hold a feeding charge, a coreless induction furnace with which the stack is adapted to cooperate and into which it is adapted to feed, means for displacing the stack and induction means for melting the charge within the furnace.

19. In mechanism for melting uncabbaged scrap, a furnace stack adapted to be removed from a furnace, a coreless induction furnace with which the stack is adapted to cooperate and into which it is adapted to feed, means for shifting the stack, a cover for the furnace adapted to be placed above the furnace in the absence of the stack and high-frequency-induction means surrounding the furnace for melting the charge within the furnace.

20. In a device for melting finely divided scrap, a pair of induction electric furnaces, a stack common to the pair and means for supporting the stack permitting shifting of the stack from a position over one of the furnaces to feed scrap into that furnace to a position over the other furnace to feed scrap into the second furnace.

21. In a device for melting finely divided scrap, a pair of induction electric furnaces, a stack common to the pair, means for supporting the stack permitting shifting of the stack from the position over one of the furnaces to feed scrap into that furnace to a position over the other furnace to feed scrap into the second furnace and cover means for the furnaces when the stack is displaced from position over them.

22. In mechanism for melting uncabbaged scrap, a furnace stack adapted to be removed from a furnace, a furnace with which the stack is adapted to cooperate and into which it is adapted to feed, means for supporting the stack permitting shifting of the stack, a cover for the furnace adapted to be placed above the furnace in the absence of the stack and high-frequency-induction means surrounding the stack and surrounding the furnace for heating the charge within the stack and for melting the charge within the furnace.

23. In an induction electric melting furnace, a crucible, an inductor about the crucible, a casing about the crucible spaced from the crucible and inductor to form a cavity and having a discharge opening in the bottom and a cover for the opening adapted to be fused with leakage of the furnace charge.

EDWIN F. NORTHRUP.
